UNITED STATES PATENT OFFICE

2,641,942

FORCE APPLYING TOOL

Otto Mueller, Dearborn, Mich.

Application May 3, 1947, Serial No. 745,845

6 Claims. (Cl. 78—52)

1

This invention relates to pressure applying devices of a fluid actuated jaw type for applying pressure for performing riveting, welding, punching and like operations, and is a continuation-in-part of applicant's Patent No. 2,487,262, issued November 8, 1947.

It has been the practice heretofore in the art to utilize fluid pressure means for performing riveting and welding operations. Such devices usually apply the force directly from the piston to the work which requires the cylinder to be mounted above the work which at times limited the application of the device because of interference. When the piston and cylinder were offset from the work, the mechanical efficiency was usually lower, which oftentimes resulted in defective work being performed.

The present invention embodies a pair of cradle jaws operated by a piston and cylinder remote from the ends which perform the operation upon the work. When the jaws are the same distance from their center of operation as the piston, the same mechanical advantage is obtained. This may be increased or decreased by changing the relative position of the piston and cylinder and the work-engaging portion of the jaws relative to the jaw centers.

The main objects of the invention are: to provide a compact pressure applying device having the operating arm located remotely from the force applying element; to provide a pressure applying device having a pair of rockable jaws mounted within an improved type yoke and operated by a cylinder and piston mounted at one end of the jaws for producing working pressure at the opposite end thereof; to provide a pair of rockable jaws having work performing arms at one end and arms on the opposite end to which a piston and cylinder are connected for applying a pressure thereto; to provide a novel connection between the arms and the piston and cylinder of the force applying element; to mount a pair of rockable jaws in a yoke in such a manner as to control the movement of the jaws when the pressure is applied thereto so that each moves a like amount relative to and from each other; to provide means for limiting the opening movement of one of said arms while permitting the other of said arms to be moved by the force applying means the full distance permitted thereby; to provide a compact pressure applying device which may be mounted upon a fixture or which may be supported on a cable to be manipulated by the operator when performing welding, riveting, punching or similar operations upon work-

2

pieces; to provide an improved mounting means for said yoke including means therein to limit the movement of one of said arms of said device; to provide a pressure plate between the movable jaws of the device which urges the workpieces together when being operated upon; to provide a device of the aforementioned type having an additional force applying means mounted in the working end of one of said jaws for applying additional pressure to the work applying element mounted in said jaw; and, in general, to provide a force applying device which is simple in construction, positive in operation and economical of manufacture.

15 Other objects and features of novelty of the invention will be specifically pointed out or will become apparent when referring, for a better understanding of the invention, to the following description taken in conjunction with the accompanying drawings wherein:

Figure 1 is a sectional view of a force applying tool embodying features of this invention;

Fig. 2 is a sectional view of the structure illustrated in Fig. 1, taken on the line 2—2 thereof;

25 Fig. 3 is a reduced, partially broken-away plan view of the structure illustrated in Figs. 1 and 2;

Fig. 4 is a broken front elevational view of a further embodiment of this invention, with parts shown in section;

30 Fig. 5 is a broken sectional view, taken along the line 5—5 of Fig. 4;

Fig. 6 is a broken sectional view of a further embodiment of this invention;

Fig. 7 is a reduced view, partially in elevation and partially in section, of a further embodiment of the structure illustrated in Fig. 6;

Fig. 8 is a diagrammatic view of the hydraulic circuit for the device illustrated in Figs. 6 and 7; and

40 Fig. 9 is a side elevational view illustrating a further embodiment of the invention.

Referring to Figs. 1 to 3, a force applying device is illustrated in the form of a riveting gun which embodies a supporting yoke 11 which is herein illustrated as comprising a pair of interconnected parallel plates 13 and 15. The upper end of each of the plates 13 and 15 is formed with an inwardly extending annular flange 17. Disposed inwardly of the flanges 17, and supported on the inner peripheral surfaces thereof, are cylindrical sleeves 21 made of bearing material. Suitable lubricating passages 22 are provided in the flanges 17 to lubricate the engaging bearing surfaces. Disposed on the center line of the flanges 17, and extending between the plates 13 and 15, is a

spool element 23 having an annular flange or shoulder 24 formed on each end thereof. The spool element 23 is secured to each of the parallel plates 13 and 15 by means of screws 25 which are threadably received in tapped, central apertures 27 extending inwardly from each end of the spool 23.

Rockably supported within the yoke 11 is a pair of jaws 29 and 31, each of which is formed intermediate the ends thereof with outwardly extending arcuate bosses 33 at each of its sides. When the jaws are positioned within the yoke 11, the outer periphery of each of the bosses 33 is in sliding engagement with substantially one half of the inner periphery of the bearing sleeves 21, and the inner periphery of each of the bosses 33 mates with the outer periphery of the spool 23 so as to be rockably supported thereon. The inner periphery of each of the jaws between the bosses 33 is provided with an inwardly extending arcuate portion 35 which is received between the shoulders or flanges 24 on the spool 23 to properly center the jaws with relation to the spool. The lower jaw 31 is shown as secured to the spool 23 by means of a key 37, for a reason which will be brought out below. In this way, it will be seen that the jaws 29 and 31 are rockably supported within the yoke 11 intermediate their ends.

The main pressure exerted by the jaws reacts through the area of engagement of the arcuate surfaces of each of the bosses and the bearing sleeve 21. This area of engagement is substantial and the bearing material prevents the scoring of the metal of the engaging surfaces and produces a work applying force to the arms 39 and 41 of the jaws 29 and 31, respectively, when a piston 43 and cylinder 45 are in an extended position.

The remote end of the piston 43 is connected to an arm 47 of the jaw 29 by means of a T-headed bolt 49. The opposite end of the cylinder 45 is similarly connected to an arm 51 of the jaw 31 by means of a T-headed bolt 53 which is identical with the T-headed bolt 49. Each of the bolts 49 and 53 have a threaded stem portion 55 and a cylindrical head portion 57 which extends transversely of the stem portion 55. Each of the cylindrical head portions 57 is provided with a central longitudinal aperture 59 which communicates, in the center of the head, with a lubricating passage 61 for lubricating the cylindrical surface of the head 57 and its engaging arm surface. The cylindrical head portion 57 of each of bolts 49 and 53 is received in a more than semicylindrical aperture 63 in its respective arm 47 or 51. The cylindrical bolt heads 57 extend outwardly on the opposite sides of their respective arm and the projecting portions are reduced in diameter as at 65. In order to retain the bolt heads against lateral movement within their arms, a washer 67 is inserted over each of the projecting ends 65 and seated against the respective arm side face, and a snap ring 69 is snapped over the ends 65 into an annular groove 71 in each of the projecting ends which prevents axial movement of each bolt head. The threaded stem 55 of the bolt 49 is threadably received in a tapped recess 73 in the remote end of the piston 43 and the threaded stem 55 of the bolt 53 passes through an aperture 75 in the bottom wall of the cylinder 45 and a nut 77 is threaded on the end of the stem 53 and seats against the upper surface of the bottom wall of the cylinder to secure the bolt

thereto. The bottom of the piston head 79 is recessed as at 80 to receive the nut 77 therein when the piston is in its bottom-most position.

The head 79 of the piston 43 is provided with grooves 81 in which elastic rings 83 are mounted for providing a seal between the inner wall of the cylinder and the exterior surface of the head 79. Similar elastic rings 85 are provided in the cylinder head 87 for sealing the rod portion of the piston 43 in the cylinder 45 for preventing the fluid in the cylinder from leaking. Fluid delivering conductors 89 and 91 are attached to opposite ends of the cylinder 45, communicating with passageways therein through which fluid is conducted to both sides of the piston head 79 for producing its movement within the cylinder 45. When fluid is delivered from the conductor 89 to the cylinder, the arms 39 and 41 of the device are moved to a separated position. When the fluid is reversed and delivered from the conductor 91 to the cylinder and expelled thereby through the conductor 89, the jaws are moved toward each other to perform a desired operation.

In the structure illustrated in Figs. 1 to 3, an aperture 93 is provided near the end of each of the arms 39 and 41 for receiving the shanks 95 of riveting dies 97 which are mounted in an aligned relation. Suitable means, herein illustrated as setscrews 99, secure the riveting dies in position within the apertures 93.

Midway between the arms 39 and 41, a resilient pressure plate 101 is provided which has an aperture 103 adjacent the outer end thereof through which the riveting die 97 of the arm 41 extends. The opposite end of the plate 101 is notched on opposite sides thereof, as at 104, and is inserted into a slot 105 in the spool 23. The screws 25 are received in each of the notches 104 on the opposite sides of the plate 101 to fixedly secure the latter to the spool 23. Due to the shape of the plate 101, and the fact that the spool 23 is keyed to the movable jaw 31, the forward end of the plate 101 will engage the under side of the workpiece 107 prior to the engagement of a rivet 109 by the riveting die 97 of the arm 41. The further movement of the arms 39 and 41 toward each other produces the swaging of the end of the rivet against the workpieces 107 and the head of the rivet 109.

Disposed on the opposite side of the spool 23 from the plate 101, and supported in the opposite parallel yoke plates 13 and 15, is a pin member 110 which is supported in the plates 13 and 15. The center portion 111 of the pin member 110 is of a larger diameter than the end portions, and the center portion 111 is eccentric with respect to the supporting end portions of the pin. The pin end portions are threaded as at 112, and nuts 114 releasably lock the pin 110 to the plate members 13 and 15. However, by loosening the nuts 114, the eccentric center portion 111 of the pin 110 can be adjusted to face either of the jaws 29 or 31 to contact one sooner than the other so as to maintain the jaws substantially normal to the vertical axis of the yoke when in the open or closed positions.

When the jaws are applied to the rivet 109, the movement to closed position will first cause the die 97 on the arm 39 and the spring pressure plate 101 attached to the arm 41 to move into engagement with the head of the rivet 109 and the workpieces 107, respectively, to force the head and sheets into intimate engagement with each other as the die 97 on the arm 41 continues to move to

perform the swaging operation. When the jaw portions 39 and 41 open thereafter by the movement of the piston into the cylinder, they will both move away from each other, and as soon as one jaw is moved so as to contact the eccentric portion 111 of the pin 110, the other jaw must thereafter move. Movement continues until the piston has advanced completely into the cylinder, at which time the last-mentioned jaw moves into engagement with the pin member 110, thereby to positively retain the jaws in position relative to the yoke.

This pressure applying device may be mounted for operation in any suitable manner, such as by suspended cables (not shown) connected to the yoke, so that it may be manually manipulated by an operator, or by suitable stationary mounting means connected to the lower end of the yoke. As illustrated in Figs. 4 and 5, the yoke 11 is shown as mounted on a stationary base 113 by means of a mounting member, generally indicated at 115. The mounting member 115 is positioned between the lower ends of the parallel yoke plates 13 and 15 and secured to each of the plates by means of screws 117 received in vertically spaced apertures 119 in each of the plates. The lower end of the mounting member 115 is bifurcated, as at 121, to receive the tongue portion of the base member 113. The mounting member 115 is secured to the base member 113 by means of a bolt 123, the head 125 of which is shown as having the opposite sides thereof cut flat so as to be nonrotatably received in a slotted recess or groove 127 in the mounting member 115.

The mounting member 115 is provided between the vertically spaced bolts 117 with a tapped recess 128 into which a boltlike element 129 is threadably received. The inner end of the bolt element 129 is recessed as at 131 to slidably receive a flanged plunger 133 therein, the rear end of which projects through an aperture 134 in the mounting member 115 and is adapted to contact the lower end of the arm 51 of the jaw 31. The plunger 133 is actuated by a spring 135 received within the bolt 129 and constantly urging the plunger 133 outwardly in the mounting member 115.

When the jaws and yoke are mounted in the mounting member 115, the eccentric pin 110 is not used as the plunger 133 replaces it and limits the closing movement of the jaw 31. When the lower end of the latter contacts the spring plunger, the upper jaw 29 will continue to close, while the lower jaw 31 is limited or slowed down in its movement due to the plunger 133 so as to maintain the proper angular relationship between the jaws 29 and 31, and the yoke 11.

In the embodiment illustrated in Fig. 6, a device similar to that illustrated in Figs. 1 to 3 is provided which is adapted to perform punching operations or the like. In this device, jaws 137 and 139 are provided which are generally similar to the jaws 29 and 31 previously described. The jaws 137 and 139 are rockably supported in a yoke 141 which likewise is generally similar to the yoke 11 previously described. However, it will be noted that the parallel plates of the yoke 141 are circular in shape and are not provided with a depending portion adapted to be received in a stationary base. However, the yoke 141 is adapted to be connected to cables or the like so as to be flexibly and movably supported, and a hand grip portion (not shown) may be provided for manipulation of the device by an operator. This device is provided with an eccentric pin 143

for performing the same operation as the eccentric pin 110 described for the previous embodiment, but does not have a spring type pressure plate as there is no need for it in this type of device.

A cylinder 145 and piston 146, identical with the piston 43 and cylinder 87 previously described, are similarly connected to the ends of the jaws 137 and 139 to open and close the jaws, and fluid delivering conductors 147 and 149 are attached to opposite ends of the cylinder 145, communicating with passageways therein, through which fluid is conducted to both sides of the piston head for producing its movement within the cylinder. A punching die 151 is received in an aperture 153 in the opposite end of the jaw 137 and secured in the aperture by means of a setscrew 155. The working end of the jaw 139 has a recess 157 therein which, when an end plate 159 is sealingly secured in the lower end thereof by means of screws 161 and an elastic ring 162, provides a cylinder in which a piston 163 is received. Suitable elastic rings 165 are provided in the piston head for preventing the fluid in the cylinder from leaking. The rod portion of the piston 163 extends upwardly through an aperture 166 in the jaw 139, and an elastic ring 167 is provided in the wall of the aperture for sealing the rod portion of the plate. The remote end of the piston 163 has a punch 168 therein adapted to cooperate with the punching die 151 to punch holes in workpieces 169. In order to prevent the piston and punch from rotating, a pin 170 is provided which is pressed into a recess 170a in the cylinder head and slidably received in an aperture 170b in the piston head.

In order to supply fluid to actuate the piston 163, the jaw 139 is bored to provide a fluid passageway 171 communicating with the upper end of the cylinder 157, and a passageway 173 communicating with the lower end of the cylinder 157. Intermediate the ends of the passageway 171 and extending outwardly therefrom, is another bored passageway 177 which, as can be seen in Fig. 8, is connected by suitable conduit means 179 through a four-way valve 181 and a pressure pump 182 to a fluid supply tank 183. Below the passages 171 and 177 is a third passageway 184 which is connected by suitable conduit means 185 to the conductor 147 which is attached to the upper end of the cylinder 145. Mounted in the jaw 139, and communicating with the passageways 177 and 171, is a pressure operated spring return type valve 187, the operation of which will be hereinafter described.

Intermediate the ends of the fluid passageway 173, the jaw 139 is bored to provide fluid passageways 189 and 190 which extend outwardly on opposite sides of the passage 173. The passage 189 is connected by a conduit 191 to the four-way valve 181 and thence to the fluid storage tank 183. The passageway 190 is connected by a conduit 193 to the fluid delivery conductor 149 attached to the lower end of the cylinder 145. Disposed in the rear end of the passageway 173, and communicating with the passageways 189 and 190, is a pressure operated spring return type valve 196, the operation of which will be described below.

In operation, when the jaws 139 and 137 are in the open position, that is, the position in which the punch and punching die are separated from each other and it is desired to close them, the fluid is pumped under pressure from the fluid pump 182 through the four-way valve 181 and

through the conduit 191. As the fluid passes through the valve 196, it is not under sufficient pressure to open the valve, and thus the fluid flows through the passage 190 and the conduit 193 into the bottom portion of the cylinder 145 to cause the working end of the jaws to close. When the piston 146 has moved upwardly to a point where the punching die 151 and the punch 163 are in contact with the work-piece 169, the pressure will build up within the cylinder 145. When this occurs, sufficient pressure will be created to open the valve 196 and force the fluid under a high pressure through the passageway 173 into the lower end of the cylinder 157, thus forcing the piston 163 upwardly so as to push the punch 167 through the workpiece and on into the punching die 151. When the pistons 146 and 163 are forced upwardly in the aforescribed manner, the fluid in the upper end of the cylinder 145 flows through the conductor 147, the conduit 185, the valve 187 and back to the storage tank, while the fluid in the upper end of the cylinder 157 flows through the passage 171, the valve 187 and back to the storage tank.

When it is desired to open the working ends of the jaws and separate the punch 167 from the punching die 151, it is necessary to remove the punch from the die before the jaws are opened. Therefore, the four-way valve 181 is actuated to connect the conduit 179 with the pump 182 to pump the fluid into the passageway 171 in the jaw 139. The fluid can then pass through the passageway 171 to the upper end of the cylinder 157, but cannot pass back into the cylinder 145 due to the fact that the valve 187 is closed and there is not sufficient pressure to open the same. When the piston 163 has moved completely down so as to withdraw the punch 169, pressure will build up in the upper end of the cylinder 157. This pressure will cause the valve 187 to open and thus allow the flow of fluid through the passageway 184 into the conduit 185 and into the fluid delivery conductor 147 in the upper end of the cylinder 145. When this occurs, the piston 146 will be forced downwardly, thus causing the working end of the jaws 137 and 139 to open, thus completing the cycle. The fluid in the lower end of each of the cylinders, when the pistons are forced downwardly, will flow through its respective conduits and valve 196 back to the supply tank 183.

In the embodiment illustrated in Fig. 7, the punching type force applying tool construction illustrated in Fig. 6 is shown as mounted in a yoke 195 formed of parallel side plates generally in the same manner as in the previous embodiments. It will be noted that the side plates of the yoke 195 have downwardly depending leg portions which are cut back on the rear face to provide clearance for the fluid conduits and which are bifurcated as at 197 at their lower ends to receive a tongue 199 of a stationary mounting base. The yoke is secured to the mounting base tongue by means of a bolt and nut 201.

Fig. 9 illustrates a further embodiment of the invention which is similar to the construction illustrated in Figs. 1 to 3. However, in this embodiment the yoke 203, instead of depending vertically with respect to the jaws of the device, extends horizontally and rearwardly from the mounting point of the jaws. Suitable mounting means 205 are provided for mounting the rear end of the yoke 203 to a stationary base, and bolts 207 are provided for securing the yoke to the mounting means 205. It will be noted

that the upper jaw 209 of this embodiment is shaped differently from the lower jaw 211 and has a vertical center portion 213 intermediate the ends thereof which positions the rear arm portion 215 of the jaw 209 well above the lower jaw 211. The lower jaw 211 extends substantially horizontally to the rear and the piston and cylinder actuating means 217 is then secured to the ends of the jaws 209 and 211 in a manner similar to that described for Figs. 1 to 3. Riveting dies 219 likewise may be provided on the working end of the jaws in a manner similar to that previously described.

What is claimed is:

1. In a force applying tool, a pair of parallel plates each having an inwardly extending annular flange in spaced aligned relation, bearing means releasably secured between said plates on the center line of said flanges, a pair of rockable arms disposed between said plates and each having outwardly extending bosses formed thereon intermediate the ends thereof, sleeve means on said plates engaging the inner surfaces of said annular flanges, the inner periphery of each of said arm bosses mating with the bearing surfaces of said bearing means, the outer periphery of each of said arm bosses mating with a portion of the inner periphery of said sleeve means, means for supporting said plates, force applying means disposed between the ends of said arms on one side of the supporting plates for moving the ends away from each other when moving the opposite ends of the arms toward each other with a predetermined pressure, and work applying elements disposed on the ends of the arms opposite to that actuated by the force applying means.

2. In a force applying tool, a pair of parallel plates each having an inwardly extending annular flange in spaced aligned relation, the inner peripheries of said flanges lying on a common center, spool means disposed between said plates on the center line of said flanges, means securing each of said plates to said spool means, a pair of rockable arms disposed between said plates and each having outwardly extending arcuate bosses formed thereon intermediate the ends thereof, sleeve means on said plates engaging the inner surfaces of said annular flanges, the inner periphery of said arm bosses being rockably supported on said spool means and the outer periphery of said arcuate arm bosses being in sliding engagement with the inner periphery of said sleeve means, force applying means disposed between the ends of said arms on one side of the supporting plates therefor for moving the ends away from each other when moving the opposite ends of the arms toward each other with a predetermined pressure, and work applying elements disposed on the ends of the arms opposite to that actuated by the force applying means.

3. In a force applying tool, a pair of parallel plates each having an inwardly extending annular flange in spaced aligned relation, the inner peripheries of said flanges lying on a common center, spool means disposed between said plates on the center line of said flanges, means securing each of said plates to said spool means, a pair of rockable arms disposed between said plates and each having outwardly extending arcuate bosses formed thereon intermediate the ends thereof, sleeve means on said plates engaging the inner surfaces of said annular flanges, the inner periphery of said arm bosses being rockably supported on said spool means and the outer periphery of said arcuate arm bosses being in sliding

engagement with the inner periphery of said sleeve means, force applying means disposed between the ends of said arms on one side of the supporting plates therefor for moving the ends away from each other when moving the opposite ends of the arms toward each other with a predetermined pressure, work applying elements disposed on the ends of the arms opposite to those actuated by the force applying means, and a pressure element supported between the ends of the arms carrying the work applying elements and selectively secured to one of said arms to be operated therewith and in advance thereof for applying a predetermined pressure between the pieces to be engaged by the work applying elements before and during the working operation.

4. In a force applying tool, a pair of parallel plates each having an inwardly extending annular flange in spaced aligned relation, the inner peripheries of said flanges lying on a common center, spool means disposed between said plates on the center line of said flanges, means securing each of said plates to said spool means, a pair of rockable arms disposed between said plates and each having outwardly arcuate bosses formed thereon intermediate the ends thereof, sleeve means on said plates engaging the inner surfaces of said annular flanges, the inner periphery of said arm bosses being rockably supported on said spool means and the outer periphery of said arcuate arm bosses being in sliding engagement with the inner periphery of said sleeve means, force applying means disposed between the ends of said arms on one side of the supporting plates therefor for moving the ends away from each other when moving the opposite ends of the arms toward each other with a predetermined pressure, work applying elements disposed on the ends of the arms opposite to that actuated by the force applying means, and cam means adjustably supported by said plates and disposed between said rockable arms on the opposite side of said spool means from said work applying means adapted to be rotated to limit the opening and closing movement of one of said rockable arms.

5. In a force applying tool, a pair of parallel plates each having an inwardly extending annular flange in spaced aligned relation, the inner peripheries of said flanges lying on a common center, spool means disposed between said plates on the center line of said flanges, means securing each of said plates to said spool means, a pair of rockable arms disposed between said plates and each having outwardly extending arcuate bosses formed thereon intermediate the ends thereof, sleeve means on said plates engaging the inner surfaces of said annular flanges, the inner periphery of said arm bosses being rockably supported on said spool means and the outer periphery of said arcuate arm bosses being in sliding engagement with the inner periphery of said sleeve means, force applying means disposed between the ends of said arms on one side of the supporting plates therefor for moving the ends away from each other when moving the opposite ends of the arms toward each other with a predetermined pressure, work applying elements disposed on the ends of the arms opposite to that actuated by the force applying means, and cam means adjustably supported by said plates and disposed between said rockable arms on the opposite side of said spool means from said work applying means adapted to be rotated to limit the opening and closing movement of one of said rockable arms.

determined pressure, work applying elements disposed on the ends of the arms opposite to that actuated by the force applying means, a pressure element supported between the ends of the arms carrying the work applying elements and selectively secured to one of said arms to be operated therewith and in advance thereof for applying a predetermined pressure between the pieces to be engaged by the work applying elements before and during the work operation, and cam means adjustably supported by said plates and disposed between said rockable arms on the opposite side of said spool means from said pressure element adapted to be rotated to limit the opening and closing movement of one of said rockable arms.

6. In a force applying tool, a pair of parallel plates each having an inwardly extending annular flange in spaced aligned relation, the inner peripheries of said flanges lying on a common center, spool means disposed between said plates on the center line of said flange, means for releasably securing each of said plates to said spool means, sleeve means positioned between said plates engaging the inner surfaces of said annular flanges, a pair of rockable arms disposed between said plates each having outwardly extending arcuate bosses formed thereon intermediate the ends thereof, the inner periphery of each of said arcuate bosses being rockably supported on said spool means and the outer periphery of each of said arcuate bosses slidably engaging the inner periphery of said sleeve means, force applying means disposed between the ends of said arms on one side of the supporting plates therefor for moving the ends away from each other when moving the opposite ends of the arms toward each other with a predetermined pressure, work applying elements on the ends of the arms opposite to that actuated by the force applying means for performing a work operation, mounting means for said device, and resiliently actuated plunger means mounted within said last-named means and adapted to engage one of said rockable arms at a predetermined point during the opening of the latter to limit the movement of said arm while allowing said other arm to continue its movement.

OTTO MUELLER.
